UNITED STATES PATENT OFFICE

2,531,628

MINNOW PAIL

Maximillian P. Janisch, Milwaukee, Wis.; Bride Janisch and Myra J. Hess executrices of said Maximillian P. Janisch, deceased

Application March 12, 1945, Serial No. 582,295

1 Claim. (Cl. 43—56)

1

This invention relates to minnow pails.

One object of the present invention is to provide a minnow pail in which the parts are combined and arranged in a manner to facilitate removal of minnows therefrom.

Another object is to provide a minnow pail in which the contained water may be readily aerated from time to time to effectively preserve the life of the minnows therein.

Other more specific objects and advantages will appear, expressed or implied, from the following description of an illustrative embodiment of the present invention.

In the accompanying drawings:

Figure 1 is a vertical sectional view of a minnow pail constructed in accordance with the present invention.

Fig. 2 is a sectional view of a modified form of false bottom that may be substituted for that shown in Fig. 1.

The minnow bucket selected for illustration comprises a substantially cylindrical sheet metal pail 10 equipped with a conventional hinged bail 11 and a removable cover 12.

In this instance the cover 12 comprises a ring-shaped stamping having a down turned peripheral flange 13 adapted to fit snugly on the rim of the pail and also having an elevated annular portion 14 encircling a large opening in the center of the cover. The opening in the cover is normally closed by a removable lid 15 having a marginal flange 16 seated on the elevated portion 14 and also having a perforated portion 17 preferably dished or depressed so as to normally assume a suspended position within the cover opening.

The pail shown is also equipped with a false bottom 18 loosely fitted therein and having a down turned peripheral flange 19. The false bottom 18 is supported by a bail 20 shaped to provide a pair of spaced vertical legs 21 guided in the cover 12 and suitably rigidly fixed at the lower ends thereof to the false bottom. The upper cross portion of the bail 20 is rockably attached to the lid 15 by suitable means, such as hangers 22 attached to the lid at diametrically opposite points on the supporting flange 16 thereof. That portion of the bail between the hangers 22 is fashioned to provide a hand grip 23 and preferably arched to facilitate entry of the fingers between it and the dished portion 17 of the lid.

The arrangement is such that the bail 20 may be readily elevated into the dotted-line position shown, carrying with it the lid 15 and the false

2

bottom 18, to elevate the minnows to the top of the pail where they may be conveniently removed through the opening in the cover 12 which has been cleared by the elevated lid. It will be noted that the false bottom 18 may thus be lifted above the level of water in the pail so that the minnows may be captured and withdrawn without contacting the water in the pail. It will be further noted that, when in an elevated or

open position, the lid 15 with its hangers 22 may be tilted so that an edge of the flange 16 thereof extends into a position transversely of and over the central opening in the cover 12. When so tilted, the lid flange 16 is engageable within the cover opening to prevent reseating of the lid on the annular portion 14 of the cover and thereby causing the lid to assume a self-sustained open position, in which position both hands of the user are free to introduce minnows into the pail.

20 The central portion 24 of the false bottom is preferably perforated to permit a free flow of water therethrough during elevation and depression thereof.

25 The false bottom 18 is also preferably fashioned to provide an air trap from which air may percolate up through the pail to aerate the water therein when the false bottom assumes the lowermost position shown. This may be accomplished in various ways. In the Fig. 1 device 30 a circular flange 25 is welded or otherwise tightly fixed to the false bottom for this purpose. This flange 25 isolates the central perforated area 24 and cooperates with the peripheral flange 19 to form an annular chamber 26. A very few minute bleed openings 27 provide slow leakage of air from this chamber.

40 It will of course be understood that whenever the false bottom 18 is elevated above the water level, to render the minnows accessible for removal in the manner above described, air enters the chamber 26, and that the air becomes trapped therein whenever the false bottom is returned to its normal lowermost position. Thereafter the air slowly escapes through the bleed openings 27 and percolates up through the water to aerate the same and thus preserve the life of the minnows.

45 The false bottom shown in Fig. 2 also functions as an aerator. In it the central perforated section 24 is dished to provide a wall 25' that cooperates with the peripheral flange 19' to form an air chamber 26' which functions in the same manner as the chamber 26 above described. Minute bleed openings 27' provide slow leakage of air from this chamber 26' upward through

the water in the pail whenever the false bottom is lowered into its lowermost position.

Various changes may be made in the embodiment of the invention hereinabove specifically described without departing from or sacrificing the advantages of the invention as defined in the appended claim.

I claim:

A minnow pail including a false bottom, said false bottom having an air trap, vertically movable actuating means extending through the top of said pail for raising and lowering said false bottom, said pail having a top opening, a lid movable to open and close said opening, and means for rockably mounting said lid on said vertically movable actuating means for actuation thereby and for permitting tilting of said lid within said top opening into edgewise engagement with the

edge of the top opening so as to sustain said lid in open position.

MAXIMILLIAN P. JANISCH.
